UNITED STATES PATENT OFFICE.

WILLIAM B. DORWARD, OF LAWRENCE, KANSAS.

CISTERN-MOLD.

No. 856,852.

Specification of Letters Patent.

Patented June 11, 1907.

Application filed December 15, 1906. Serial No. 347,989.

To all whom it may concern.

Be it known that I, WILLIAM B. DORWARD, a citizen of the United States of America, residing at Lawrence, in the county of Douglas 5 and State of Kansas, have invented new and useful Improvements in Cistern-Molds, of which the following is a specification.

This invention relates to cistern molds, and one of the principal objects of the same 10 is to provide a mold which can be adjusted vertically to form a cistern of any required depth.

Another object is to provide a cistern mold in which the parts can be quickly assembled 15 and adjusted for use, and which can be quickly detached and removed from within the cistern.

These and other objects may be attained by means of the construction illustrated in 20 the accompanying drawings, in which:

Figure 1 is a vertical section through a mold made in accordance with my invention, and showing the cistern molded thereon. Fig. 2 is a plan view of the upper portion of 25 the mold, the dome portion being removed. Fig. 3 is a detail side elevation of an adjustable connecting bolt. Fig. 4 is a plan view and partial section of the upper end of the mold.

Referring to the drawings for a more particular description of my invention, the numeral 1 designates a base secured to a transverse plank or support 2. Connected to the base 1 is a vertical tube 3 disposed centrally 30 in the mold, said tube being held in position within the support 1 by clamping screws 4. Adjustably supported within the tube 3 is a column 5, said column being held in adjusted position within the tube 3 by means 35 of clamping screws 6 passing through the tube 3 and bearing against the column. Surrounding the tube 3 near its lower end is a collar 7 provided with a series of vertical pins 8, said collar being secured to the tube 40 by means of binding screws 9. An angle iron ring 10 extends around the bottom inner wall of the mold, and is provided with pins 11 similar to the pins 8 and also with a series of spacing pins 12 between which 45 and the outer flange 13 of the ring, the side walls 14 of the bottom staves of the mold are positioned. Rods 15 provided with tubular T-couplings 16 at each end are fitted upon the pins 8 and 11 to brace the 50 inner wall 14 of the mold. At a point nearly central of the mold and connected to the

tube 3 is a ring 17 provided with pins 18 and secured to the tube 3 by means of a binding screw 19. Radial brace rods 20 provided with T-couplings 21 at their ends are 55 detachably connected to the pins 18 at one end and to pins 22 at their opposite end, said pins 22 being supported upon an angle iron ring 23 supported in keepers 24 secured to the inner surface of the plates or staves 60 14. At the upper portion of the column 5 a similar ring carrying pins is connected by braces 25 secured to pins 26 rising from an angle iron ring 27 fitted in keepers 28.

The side plates or staves 14 are connected 70 together at their joints by means of angle plates 29 through which extend curved adjusting rods 30 provided with outwardly movable reversely disposed nuts 31. At the vertical meeting edges of the staves 14 pivoted buttons 32 are provided, said buttons being turned upon their pivotal points to hold the meeting edges in alinement. It is to be noted that the plates or staves 14 are 75 sectional, there being shown three vertical 80 sections and each section comprising a separate ring or series of plates 14.

The dome portion of the mold consists of a series of wooden bars or blocks 33 having curved outer surfaces and disposed upon the 85 angle iron ring 27, said blocks being braced outwardly by means of the rods 25. Curved angle irons 34 extend from the blocks 33 to the central opening at the top of the mold and disposed upon the outer sides of said 90 angle irons 34 are the radially arranged plates or staves 35 forming the curved dome portion of the cistern. To brace the dome portion vertically a series of hinged braces 36 connected to a transverse bar 37 by means of 95 hinges 38 are secured at their lower ends by means of pins 39 passing through feet 40 formed on the lower ends of the braces 36 resting upon planks 41.

The ring 27 comprises several sections, as 100 shown in Fig. 2, said sections being adjustably held together by means of swinging bolts 42, said bolts having downwardly turned ends 43 and 44, the end 44 adapted to fit within an aperture in one of the sections 105 27 and the other end 43 being threaded to receive a nut 45. By means of these bolts the sections 27 may be readily detached by turning the nut 45 a short distance upon the end 43 to permit the end 44 to be removed from 110 the abutting section. Pivoted buttons 46 are utilized for holding the dome staves in

position. A ring-like collar 47 is seated upon the upper end of the dome and provided with adjusting bolts 48 and angle plates 49 similar to the bolts 30 and plates 29 for adjusting 5 said collar outwardly to form the neck of the cistern. A ring 50 fits around the outer surface of the cistern neck and a sewer connection 52 is disposed upon the dome, as shown in Fig. 1.

10 From the foregoing it will be obvious that my cistern mold can be quickly assembled and the parts quickly detached after the cistern has been molded. The column 5 may be adjusted vertically within the tube 3 for a 15 cistern of greater depth whenever required.

Having thus described the invention, what I claim is:

1. In a cistern mold, the combination of a central standard, a column fitted adjustably 20 in said standard, rings on said standard and column, upwardly projecting pins fitted to said rings, an outer angle iron ring provided with upwardly projecting pins, and a brace

rod having T-couplings fitted to the ends thereof to engage the pins, side plates for said 25 mold, and keepers for said angle iron ring carried by said plates.

2. In a cistern mold, the combination of a central tubular standard, a column fitted adjustably in said standard, rings on said 30 standard and column, upwardly projecting pins fitted to said rings, an outer angle iron ring provided with upwardly projecting pins, brace rods having T-couplings fitted to the ends thereof to engage said pins, side plates 35 for said mold, keepers for said angle iron ring carried by said plates, and a dome portion consisting of curved angle irons supported by hinged braces.

In testimony whereof, I affix my signature 40 in presence of two witnesses.

WILLIAM B. DORWARD.
